(57) **CLAIM**

The ornamental design for a lock pin puller as shown and described.

DESCRIPTION

FIG. 1 is an enlarged perspective view of a lock pin puller; FIG. 2 is a front elevational view of the lock pin puller of FIG. 1;

FIG. 3 is a rear elevational view of the lock pin puller of FIG. 1;

FIG. 4 is a right-side elevational view of the lock pin puller of FIG. 1;

FIG. 5 is a left-side elevational view of the lock pin puller of FIG. 1;

FIG. 6 is a top plan view of the lock pin puller of FIG. 1; FIG. 7 is a bottom plan elevational view of the lock pin puller of FIG. 1; and,

FIG. 8 is an enlarged alternate front perspective view of the lock pin puller of FIG. 1.

The portions shown in broken line do not form part of the claimed design.
